MEANS FOR SETTING-UP COLLAPSIBLE CONTAINERS

Earl W. Barnard, Morris, Ill., assignor to Morris Paper Mills, Morris, Ill., a corporation of Illinois

Application July 17, 1933, Serial No. 680,741

19 Claims. (Cl. 93—55)

The present invention relates to the setting up or erection of fibre containers, and has particular reference to a device for the setting up of containers of the type described in copending application of Lawrence Arneson, Serial No. 680,743 filed July 17, 1933, which container is characterized by a body portion with tongues along its lower edge and a bottom member having complementary projections adapted to interlace with said tongues to form a rigid bottom structure for the container, at the same time maintaining the container in erect condition.

A principal object of the invention is to provide means for setting up a container of the described type, in which the body portion of the container is interlocked with the bottom portion without employment of additional securing means, such as metallic bands or the like.

An additional object is the provision of a simple setting-up mechanism and method of erection of collapsible containers of the type described herein.

In the accompanying drawings:

Fig. 1 is a plan view of a device constructed in accordance with my invention;

Fig. 2 is a side view of the device shown in Fig. 1;

Fig. 3 is a fragmentary plan view showing an early stage in the erection of the container;

Fig. 4 is a cross section taken along line 4—4 of Fig. 3;

Fig. 5 is a fragmentary view showing a later stage in the erection of the container;

Fig. 6 is a cross sectional view taken along line 6—6 of Fig. 5;

Fig. 7 is a plan view disclosing a modified form of the device illustrated in Figs. 1 to 6; and

Fig. 8 is a perspective view of a modified form of container setting-up mechanism constructed in accordance with my invention.

Containers of the type to which my invention pertains are provided with a fibre body portion 10 composed of fibre board or other similar material and having longitudinal score lines 11. Attached to the lower edge of the body portion 10 is a series of bottom-engaging tongues 12 which ordinarily extend in the plane of the body portion. These tongues are cut away adjacent each other to receive the fingers 13 of bottom member 14. When the tongues 12 are in the horizontal position shown in Fig. 3, the bases of the tongues form an annular horizontal shelf or platform, the inner diameter of which is somewhat less than the diameter of the body portion 10 of the container. The bottom member 14 has a

diameter which is substantially equal to the inner diameter of the shelf formed by the base portions of the tongues 12 and when the container is in erect position the fingers 13 on the bottom member 14 partially override the shelf formed by the tongues while the free ends of the tongues override the bottom member 14, thereby forming a firm interlock which prevents the bottom member from being pressed downwardly beyond a horizontal position.

To erect or set up this type of container I have provided a device which is effective and simple in operation.

As shown in Figs. 1 to 7, the horizontal base 20 has mounted thereon a body portion receiver 21, the upper portion of which is flanged outwardly into a funnel-like shape. The lower portion of the receiver is secured to a horizontal plate 22, and the latter is screwed or otherwise fastened to the base member 20 to provide a rigid structure. The body portion receiver may be bifurcated or split in halves which may be pivoted together as at 23, for ease of assembly, the opposite halves being secured by a suitable bolt, as shown at 24. In its interior the body portion receiver will correspond to the shape of the body portion of the container which ordinarily will be circular in cross section.

Within the body receiver 21 is mounted a bottom member positioning element 25 which consists of a round block, preferably of wood, of less diameter than the diameter of the receiver 21, and surrounded by a metal band 26, the latter having projections 27 extending upwardly above the wood block and suitably spaced to receive the fingers 13 on the bottom member 14. As will be seen in Figs. 1, 4, and 6, the bottom member is held in spaced relation from the lowest part of the body portion receiver 21 and is prevented from rotation by means of engagement 30 of the projections 27 with the fingers 13.

Mounted on the base 20 is a reciprocating plate 28 which operates in a substantially horizontal plane. The plate is provided with a base frame 29 and track plates 30 along the edges of the base frame. An end plate 31 is provided to limit the outward movement of the plate. This plate is adapted to reciprocate in a horizontal slot 32 in the body receiver. The slot 32 and plate 28 are located on a slightly higher level than the level 35 of the bottom member positioning element 25 so that when the plate 28 is in its inner position it forms a false bottom for the body portion receiving member. As the false bottom completely closes the body portion receiver 21, the body por- 50 55

tion of a container may be positioned on the false bottom without contacting the bottom member, as will be seen in Fig. 4. When the plate 28 is reciprocated to its outer position, the body portion receiver 21 is entirely open and the body portion of the container may then be pressed downwardly into engagement with a bottom member. Ordinarily, the plate 28 is biased toward its outer position by the action of spring 33 acting on one end of the fulcrumed lever 34, the opposite end of the lever pressing against pin 35 mounted on the plate 28. It will be seen that inward movement of the plate 28 is against the action of the spring. By grasping the handle 36 on plate 28 the latter may be pressed to its inner position. To maintain the plate in this inner position a spring-pressed catch 37 is provided, the point 38 of which engages notch 39 in the plate 28. When it is desired to retract the false bottom from the body portion receiver 21, it is merely necessary to press upon the handle of the catch 37, whereupon the hook 38 is released from the notch 39 and the spring 33 causes the plate to slide to its outer position, the reciprocal action of the plate being illustrated in Fig. 1.

To erect a container with this device, a bottom member 14 is placed on the bottom member positioning element 25 in such a manner that the fingers 13 on the bottom member are engaged between adjacent projections 27 of the metal band 26.

The plate 28 is then pressed to its closed position and engaged with the catch 37 to form a false bottom for the body portion receiver.

A collapsed body portion is then distended into substantially cylindrical form and pressed downwardly to the outwardly flanged open end of the body receiver 21 being canted and turned on its axis as it descends. This operation causes the tongues 12 on the bottom of the body portion to turn inwardly. As the body portion is pressed downwardly into the receiver 21, the partially rotated tongues 12 strike the false bottom or plate 28 and are rotated thereby into the substantially horizontal position shown in Figs. 3 and 4. The lower edge of the body portion is adjacent the false bottom at this stage of the operation.

After the container is in the position shown in Figs. 3 and 4 the catch 37 is released and the false bottom slides out of the body portion receiver. The body portion 10 is then pressed downwardly to the bottom of the receiver 21, its lowermost position being shown in Figs. 5 and 6. When the edge of the body portion strikes the base 20 the tongues 12 will have been rotated upwardly by their contact with the raised bottom positioning element 25 and/or the fingers 13. If the position of the body portion is such that the fingers 12 are adjacent the projections 27 on the bottom member positioning element the tongues 12 and the fingers 13 will assume an interlaced relation such as shown in Fig. 5. That is, the fingers 13 will partially overlie the shoulder portions of the tongues 12 and the free ends of the latter will overlie the bottom member 14.

However, the body member is ordinarily pressed down into the bottom of the receiver 21 without regard to the relative position of tongues 12 and fingers 13 so that in a great many instances the tongues will be positioned adjacent the fingers themselves and will be rotated upwardly by the latter. It is obvious that there can be no interlock of the elements when in this position, but in order to obtain such a relative position between the tongues and fingers as to effect an interlock-

ing relation, it is merely necessary that the body portion be twisted or rotated. When the proper position is reached the resiliency of the tongues which tend to cause them to turn to a horizontal position will cause the tongues to snap into position between adjacent fingers, thereby effecting the interlacing relation.

After the body portion of the container and the bottom member are in the position shown in Figs. 5 and 6, the erection of the container is completed by merely withdrawing the body portion from the setting-up mechanism. The resiliency of the tongues causes them to assume an approximately horizontal position upon withdrawal of the container from the setting-up device. By inserting an inner bottom member and pressing the same downwardly against the bottom member 14 and the tongues 12, a flat bottom is obtained. In some cases it will be found satisfactory merely to fill the container with the desired commodity for flattening out the bottom portion.

In the embodiment of my invention shown in Fig. 7, the plate 28 is arcuate in shape and its path of reciprocation is likewise arcuate. The rod 34 is pivotally secured to a pin 37 on the plate and the arm has its intermediate pivot at the center of an imaginary circle of which the path of reciprocation of the plate 28 forms a segment.

In many instances the form of device shown in Fig. 8 will be found desirable, particularly since in this modification the false bottom is eliminated. As shown in Fig. 8, the body portion receiving element 21 and its attaching flange or plate 22 are mounted on the table portion 40 of a suitable frame structure 41. It will be noted that the table portion 40 has an opening therein which is of substantially the same diameter as the inside diameter of the body portion receiver 21.

On the inside of the body portion receiver 21 and adjacent the lower portion thereof is mounted a horizontal ledge 42 which corresponds in position to the position of the member 20 of the modification described heretofore. That is, the ledge is positioned to receive the bottom edge of the body portion of the container. When the body portion of the container is pressed downwardly into receiver 21, as described heretofore, the ledge 42 causes fingers 12 on the container to rotate into horizontal position.

The bottom positioning member 25 is mounted upon a vertically reciprocating shaft 43. Below member 25 the shaft 43 is journaled in a support 44. This support carries a pin 45 which extends into a helical groove 46 in shaft 43. It will be observed that upon vertical movement shaft 43 will have a twisting action which causes the bottom positioning member 25 to rotate.

The lower end of shaft 43 is provided with a ball 47 which fits into a socket member 48 of vertical shaft 49, the lower end of the latter being pivotally secured to one end of a foot lever 50. By pressing the pedal 51 mounted on the opposite end of lever 50, shafts 43 and 49 and bottom positioning member 25 are moved.

A bottom member 14 is placed on the positioning member 25 shown in Fig. 8, and, after a container body portion is properly positioned in the member 21 with tongues 12 in substantially horizontal position, foot pedal 51 is pressed, thereby causing the bottom position member 25 to be pressed upwardly beyond the lower edge of the container. In its uppermost position member 25 is in substantially the same position as shown in Fig. 6, and the bottom 14 and fingers 12 likewise

assume the position shown in Fig. 6. That is, the bottom member 14 is moved upwardly into interlocking relation with the fingers on the body member. As the member 25 progresses upwardly it is caused to rotate, as described heretofore, and this rotation insures that the projections 13 will enter the openings between adjacent fingers 12. After the projections 13 have interlocked with fingers 12, continued rotation of the bottom positioning member 25 merely causes the body portion to rotate with the bottom section. By releasing foot pedal 51 bottom positioning member 25 is retracted to its down position and erection of the container is complete.

16 In order for the bottom member to be pressed upwardly beyond the ledge 42, it is preferred that the latter be of sufficiently large inside diameter to permit clearance, although in some instances it may be found satisfactory to allow the projections 13 on the bottom member to snap past the ledge. It will be understood that the outside diameter of the bottom positioning member 25 is smaller than the inside diameter of ledge 43 to provide clearance for its being pressed upwardly with the bottom member 12 beyond the ledge.

Various other modifications of the structure which has been described herein for the purposes of illustration and explanation are possible without departing from the spirit of my invention, and all such embodiments are intended to be defined in the appended claims.

I claim:

1. In a device for setting up containers of the type having a body portion with tongues on the lower edge thereof adapted to interlock with a bottom member having complementary interlocking elements, means for rotating the tongues along the lower edge of said body member into inwardly turned position, means for supporting a bottom member having complementary interlocking elements, and means for producing relative motion between said body portion and bottom member, whereby to interlock said tongues and said bottom member.

2. A device for setting up containers of the type having a body portion with tongues on the lower edge thereof adapted to interlock with a bottom member having complementary interlocking means, comprising a funnel-like body portion receiving element, and a bottom member positioning element positioned in said receiving element and spaced upwardly from the lower portion thereof.

3. In a device for setting up containers of the type having a body portion with tongues on the lower edge thereof and a bottom member having complementary interlocking means adapted to interlock with said tongues, a flanged body portion receiver, a bottom positioning element of less diameter than the diameter of said receiver positioned in said receiver and spaced from the lower portion thereof, and a retractable false bottom operable in one position to cover said bottom positioning element.

4. In a device for setting up containers of the type having a body portion with tongues on the lower edge thereof and a bottom member having complementary interlocking means adapted to interlock with said tongues, a flanged body portion receiver, a bottom member positioning element of less diameter than said receiver positioned in said receiver and spaced from the bottom thereof, and means on said bottom position-

ing element for preventing rotation of a bottom member positioned thereon.

5. In a device for setting up containers of the type having a body portion with tongues on the lower edge thereof and a bottom member having complementary interlocking means adapted to interlock with said tongues, a flanged body portion receiver, a raised bottom member positioning element located in the lower portion of said flanged body portion receiver, and a plate mounted for reciprocal motion in a substantially horizontal plane into and out of said receiver above said bottom positioning element.

6. In a device for setting up containers of the type having a body portion with tongues on the lower edge thereof and a bottom member having complementary interlocking means adapted to interlock with said tongues, a base member, a raised bottom receiving element positioned on said base, a substantially annular body portion receiver positioned on said base in spaced relation to said bottom member positioning element, said receiver having a flanged upper portion and a horizontal slot positioned above said bottom member receiving element, a plate mounted for reciprocation into and out of said slot, and spring-pressed means tending to withdraw said plate from said slot.

7. In a device for setting up containers of the type having a body portion with tongues on the lower edge thereof and a bottom member having complementary interlocking means adapted to interlock with said tongues, a body portion receiver, a bottom member positioning element, and means for producing relative movement between said receiver and said member whereby to interlock said tongues and said bottom member.

8. In a device for setting up containers of the type having a body portion with tongues on the lower edge thereof and a bottom member having complementary interlocking means adapted to interlock with said tongues, a body receiver being open in its lower portion, a ledge along the inner side of said receiver, a bottom positioning member, and means for producing vertical reciprocation of said member above and below said ledge.

9. A device as described in claim 8, including means for rotating the bottom positioning member.

10. A device for setting up a fibre container of the type having a body portion with tongues hinged along the lower edge thereof and a bottom member having means for interlocking with said tongues, comprising means for rotating said tongues inwardly of the body portion of the container, and means for positioning the bottom member within the body portion of the container above the lower edge thereof, whereby to permit interlocking of said tongues and said bottom member from the under side of said bottom member.

11. A device for setting up a fibre container of the type having a body portion with tongues hinged along the lower edge thereof and a bottom member having means for interlocking with said tongues, comprising means for rotating the hinged tongues of the body portion inwardly, and means for positioning a bottom member within said body portion and spaced upwardly from the bases of said tongues.

12. A device for setting up a fibre container of the type having a body portion provided with tongues at its end portion and an end closure having means for interlocking with said tongues, comprising a body portion receiving member adapted to present the body portion of said carton in posi-

- tion for securement of said end closure, and an end closure positioning means adapted to position the end closure of said carton in position for engagement with the tongues on said body portion when the latter is presented by said receiving member. 5
13. A device for setting up a fibre container of the type having a body portion provided with inwardly deflectable tongues on its end portion and an end closure having means for interlocking with 10 said tongues, comprising a body portion receiving member adapted to present the body portion of a carton in position for securement of said end closure thereto, and an end closure positioning member adapted upon relative motion with said body member to enter said body member and position said end closure therewithin for engagement with said tongues. 15
14. A device for setting up a fibre container of the type having a body portion with tongues hinged along the lower edge thereof and a bottom member having means for interlocking with said 20 tongues, comprising a body portion receiving member adapted to present the body portion of a container in distended shape and in position for securement of an end closure thereto, means 25 for positioning a bottom member above the bottom of and within a body portion in said receiving member, and means for initially supporting a body member above said bottom positioning member. 30
15. A device for setting up collapsible tubular containers of the type having a body portion with inwardly movable tongues on one end thereof and a bottom member having complementary interlocking means spaced from its periphery, comprising 35 means for presenting the body portion in distended condition with the tongue members thereon extending inwardly, and means for presenting a bottom member inwardly of said body portion for producing an interlock with said tongues from the outer side of said bottom member. 40
16. A device for setting up collapsible tubular containers of the type having a body portion with inwardly movable tongues on one end thereof and a bottom member having complementary interlocking means spaced from its periphery, com- 45
- prising means for presenting the body portion in distended condition with the tongue members thereon extending inwardly, means for presenting a bottom member inwardly of said body portion for producing an interlock with said tongues from the outer side of said bottom member. 5
17. A device for setting up collapsible tubular containers of the type having a body portion with inwardly movable tongues on one end thereof and a bottom member having complementary interlocking means spaced from its periphery, comprising 10 means for presenting the body portion in distended condition with the tongue members thereon extending inwardly, means for presenting a bottom member inwardly of said body portion for producing an interlock with said tongues from the outer side of said bottom member, and means for aligning said tongues and said complementary interlocking means. 15
18. A device for setting up collapsible tubular containers of the type having a body portion with inwardly movable tongues on one end thereof and a bottom member having complementary interlocking means spaced from its periphery, comprising 20 means for presenting a body portion of a container in distended condition, and means for producing an interlock between the tongues on said body portion and a bottom member from the outer side of the latter. 25
19. A device for setting up collapsible tubular containers of the type having a body portion with inwardly movable tongues on one end thereof and a bottom member having complementary interlocking means spaced from its periphery, comprising 30 means for presenting the body portion of a container in distended condition, means for aligning the tongues on said body portion with the interlocking means on a bottom member, and means for producing an interlock between said tongues and said interlocking means from the outer side of said bottom member. 35
